UNITED STATES PATENT OFFICE

107,496

DESIGN FOR A COMBINED CHIMNEY AND LAMP SHADE

Sylvester A. Baker, San Francisco, Calif.

Application June 1, 1937, Serial No. 69,649

Term of patent 7 years

To all whom it may concern:

Be it known that I, Sylvester A. Baker, a citizen of the United States of America, residing at San Francisco, in the county of San Francisco and State of California, have invented a new, original, and ornamental Design for a Combined Chimney and Lamp Shade, of which the following is a specification, reference being had to the accompanying drawing, forming a part thereof.

The figure is a side elevational view of a combined chimney and lamp shade showing my new design.

The drawing is lined for contrasting color.

I claim:

The ornamental design for a combined chimney and lamp shade substantially as shown and described.

SYLVESTER A. BAKER.
